UNITED STATES PATENT OFFICE

2,666,462

HYDRAULICALLY OPERATED LOG KICKER

Dow C. Richardson, Metropolis, Ill.

Application May 9, 1952, Serial No. 286,920

5 Claims. (Cl. 143—96)

1

The present invention relates to log transfer apparatus for use in sawmills of either a portable or stationary character, and more particularly has reference to an apparatus for moving the logs from a deck, skidway or similar supporting surface to the log carriage or other means for moving the log to be sawn past the saw, such apparatus being referred to in the trade as a "log kicker."

While numerous arrangements have heretofore been provided for "kicking" the log onto the carriage, such apparatus either being actuated by power means or manually, these prior assemblies have not proven too satisfactory, in that they are quite complex as to structural details which materially increases the manufacturing and maintenance costs so that many mills are not able to employ the apparatus. Additionally, the majority of the power operated kickers have utilized steam as the medium for operating the power cylinder which requires relatively large cylinders to efficiently handle the load and, in addition, necessitate a plant for generating the required steam. Furthermore, these power operated units are difficult to install in all types of mills and a considerable amount of time is required to set up the apparatus for operation.

Accordingly, one of the important objects of the present invention is to provide a power unit for operating the log transfer means which will overcome the foregoing and other objectionable features now present in the art.

Yet another object of my invention is to provide a "log kicker" wherein a hydraulic power means is employed for operating the log moving member of the kicker.

And yet another object of the present invention is to provide a log kicker wherein the cylinder carries means externally thereof in proximity to the ends of the cylinder, cooperating with a stop movable with the piston rod for limiting the extent of reciprocatory movement of the piston rod in both directions of movement of the piston rod.

And still a further object of the invention is to provide a log kicker assembly comprising but few cardinal working parts, which is positive and efficient in operation and which can be inexpensively manufactured and maintained.

With the foregoing and other objects in view, the invention consists in the details of construction, and in the arrangement and combination of parts to be hereinafter more fully set forth and claimed.

In describing the invention in detail, reference

2

will be had to the accompanying drawings forming part of this application, wherein like characters denote corresponding parts in the several views, and in which:

5 Figure 1 is a view in side elevation, partly broken away, of a log kicker constructed in accordance with the present invention.

Figure 2 is a view similar to Figure 1, showing the position of the parts after a log has been kicked onto the sawmill carriage (not shown).

Figure 3 is a top plan view of Figure 1.

Figure 4 (sheet 1) is a view taken along the line 4—4 of Figure 1, the view looking in the direction of the arrows, and

15 Figure 5 is an elevational view, partly broken away and partly in cross section, showing the coacting stop members provided on the cylinder and piston rod, respectively.

Figure 1 depicts schematically a log deck or skidway 10, a concrete or heavy timber foundation 11 spaced below the deck 10, an intermediate timber 12, and log kicker assembly indicated generally 13 supported by the timbers 11 and 12, respectively.

20 25 The kicker 13 comprises a cylinder 14 having an extension 15 at the lower end thereof, the extension 15 being pivoted to spaced lugs 16 of a base plate 17, the base plate being bolted or otherwise conveniently attached to the timber foundation 11, the pivot connection being indicated 18. A piston rod 19 provided with a piston (not shown) is reciprocably mounted within the cylinder 14 and the piston projects through a packing gland 20 at the upper end of the cylinder. The packing gland may have a hexagonal head to facilitate removal of the gland from the cylinder, or the head may be round, having apertures therein for receiving a tool to permit rotation of the head.

30 35 The upper or free end of the piston rod 19 is pivotally connected as shown at 21 to an arm 22 welded to and projecting rearwardly from a kicker arm 23. The kicker arm 23 is carried by a cross shaft 24, the shaft 24 being journaled in a bearing 25 bolted to the upper face of each timber 12, the bearing 25 being disposed below the upper face of the skidway 10. The arm 23 has an inwardly curved front edge 26, a curved upper edge 27 and flat lower and rear edges 28

40 45 and 29, respectively. Of course the shaft 24 carries two arms 23, as shown in Figure 3, but for the sake of simplicity, the description is limited to but a single arm.

Hydraulic fluid from a source of fluid (not shown) is admitted into the interior of the cyl-

inder 14 through a lower port 30 and an upper port 31, through flexible pipe connections 32 and 33, respectively, the connections leading to the supply source. A control valve of any convenient type, together with an operator therefor, is interposed in the conduits 32 and 33 between the cylinder and the source of fluid for controlling the fluid circuit to the cylinder 14. Obviously, when fluid is admitted into the port 30, the piston will be moved upwardly, the fluid being exhausted through the conduit 33, while admitting the fluid into the upper end of the cylinder through the port 31 will move the piston in the opposite direction, the fluid below the piston being displaced through the conduit 32.

As previously mentioned, an important feature of the present invention is to provide means which will limit the extent of upward movement of the piston rod 19 and the extent of downward movement of the piston rod. This arrangement is perhaps best shown in Figures 2 and 5 where it will be noted that an annular metal ring 34 is welded or otherwise secured to the outer periphery of the cylinder 14 at a point below the port 31. A plurality of leather or rubber disks 35 are bolted or otherwise conveniently secured to the lower planar face of the ring 34, and while the drawings show two such disks 35, it is obvious that a greater number may be used. The disks 35 are preferably in the form of two semi-circular parts to facilitate installation and removal for replacement or repair purposes, although these can be in the form of continuous annulus.

The ring 34 and the disks 35 are each provided with slots 36 which are diametrically opposed and are in registry (Figure 5) for defining a passageway extending throughout the height of the ring and the disks. These passageways are adapted to receive a pair of spaced parallel arms 37 which are pivoted at their upper ends to the pivot connection 24 between the piston rod 19 and the arm 22, the slots being of such size that the arms 37 may freely pass therethrough. An annular metal flange 38 is welded as shown at 39 to the lower ends of the arms 37, and the diameter of the flange 38 is the same as that of the ring 34 and the disks 35. The ring 34, disks 35 and flange 38 cooperate, as will later be described, to constitute a stop for limiting the upward movement of the piston rod 19.

A metal ring 40 of the same diameter as the ring 34 is welded to the cylinder barrel at a point immediately above the lower port 30, as shown at 41, and disks 42 similar to the disks 35 are carried by the ring 40. Since the disks 42 are not subject to displacement, so to speak, with respect to the cylinder barrel, these disks need not be bolted or otherwise attached to the ring 40, but obviously these disks can be secured thereto in the same manner as the disks 35 are attached to the ring 34. The ring 40, disks 42 and the flange 38 coact to constitute the stop for the downward movement of the piston rod 19.

In operation, and assuming that a log is located forwardly of the curved end 26 of the arm 23, it will be appreciated that if the controls are manipulated to admit fluid into the lower end of the cylinder through the port 30, the piston will be moved upwardly, and consequently the arm 23 will be moved simultaneously therewith toward the left (Figure 2), thus kicking the log onto the carriage, the upper edge 21 preventing the other logs from rolling down the deck. Manifestly, the upward extent of movement of the piston rod will be stopped when the flange 38

strikes the disks 35, and consequently, there is no danger of the arm 23 moving too far about its point of pivot. By admitting fluid into the upper end of the cylinder, the piston will be moved downwardly in the cylinder, thereby moving the arm 23 in a clockwise direction about its point of pivot, whereupon the curved end 26 will prevent the logs from rolling past the arm, as clearly shown in Figure 1. Needless to say, the downward movement of the piston into the cylinder will be arrested when the flange 38 engages the disks 42 and hence, the arm 23 cannot turn beyond its effective distance in a clockwise direction.

15 The hydraulic system includes a supply tank connected through piping with a conventional pump, a conduit leading from the pump to a four-way valve, conduits extending from the valve to the ports 30 and 31 of the cylinder, there being an exhaust line from the valve to the oil tank. The valve can be actuated by a suitable operator such as a foot pedal or the like. In addition, the log kicker can be used in combination with a power operated log turner such as shown in my co-pending application Serial Number 220,619 filed April 12, 1951 and, in this connection, the pipe connection from the pump will pass through the four-way valve which is used for operating the log turner power cylinder.

20 30 This invention is not to be confined to any strict conformity with the showing in the drawing but may be changed or modified so long as such changes or modifications mark no material departure from the salient features of the invention as expressed in the appended claims.

I claim:

1. A log transfer apparatus for use with a sawmill having a log deck, a kicker arm pivotally mounted for movement about a horizontal axis relative to the log deck, a support member below the log deck, a cylinder mounted on the support member, the piston rod of the cylinder being pivotally connected to the arm, a source of hydraulic fluid, conduits extending between the source of fluid and the upper and lower ends of the cylinder, valve means interposed in the conduits, a control member for actuating the valve means to control the fluid flow to and from the cylinder, a stop element carried by the outer periphery of the cylinder in proximity to the upper end thereof, at least one rod connected to the piston rod at the point of pivot of the piston rod to the arm, the rod extending longitudinally of the piston rod in parallel relation to the piston rod, said stop element on the cylinder having an opening therein through which the said rod extends and a flange surrounding the cylinder below the said stop element anchored to the lower end of said rod so that movement of the piston rod simultaneously moves the rod and the flange whereby engagement of the flange with the stop element limits the upward extent of the piston rod.

2. A log transfer apparatus as defined in and claimed by claim 1 further characterized in that said cylinder is provided with a second stop element adjacent the lower end thereof so that when fluid is admitted into the upper end of the cylinder the extent of downward movement of the piston rod will be arrested when the flange engages the second mentioned stop element.

3. A log transfer apparatus as defined in and claimed by claim 2 further characterized in that said stop element comprises an annular flange anchored to the outer periphery of the cylinder.

and a plurality of superposed resilient disks secured to the lower face of the annular flange to constitute a bumper.

4. A log transfer apparatus as defined in and claimed by claim 3 further characterized in that said second named stop element comprises an annular flange fixedly secured to the periphery of the cylinder, and a plurality of superposed resilient disks in facial contact with the upper surface of said annular flange.

5. A log transfer apparatus for use with a sawmill having a log deck, a kicker arm pivotally mounted for movement about a horizontal axis relative to the log deck, a support member below the log deck, a cylinder mounted on the support member, the piston rod of the cylinder being pivotally connected to the arm, a source of hydraulic fluid, conduits extending between the source of fluid and the upper and lower ends of the cylinder, valve means interposed in the conduits, a control member for actuating the valve means to control the fluid flow to and from the cylinder, a stop element carried by the outer periphery of the cylinder in proximity to the upper end thereof, a pair of parallel rods disposed on

opposite sides of and in parallelism to the piston rod, the upper ends of the rods being connected to the point of pivot of the piston rod to the arm, the stop element being provided with diametrically opposed openings through which said rods extend, a flange surrounding the cylinder below the stop element fixedly secured to the lower ends of the said rods and defining a complementary stop element so that when fluid is introduced into the lower end of the cylinder to move the piston toward the upper end thereof, the flange engages the said stop element to thus limit the extent of upward movement of the piston rod thereby restricting the amount of pivotal movement of the kicker arm.

15 DOW C. RICHARDSON.
